UNITED STATES PATENT OFFICE.

JOSEPH S. COCHRAN, OF STOCKTON, CALIFORNIA.

SALES-INDICATING CONTAINER.

Application filed December 7, 1925.; Serial No. 73,691.

This invention relates to improvements in apparatus for use in "self-selling" stores, or those in which the customers help themselves to the goods and which therefore require the use of but a small force of clerks and other help to adequately run the store.

This system is now mainly used in connection with the sale of groceries and the like, but I contemplate using this self-selling principle in connection with a drug-store, especially for selling proprietary or patent medicines which come wrapped in plainly labeled packages; and also all standard drugs and medicines which are likewise dispensed in package form or in bottles.

The principal object of my invention is to provide containers for such package goods, arranged in cases so that the goods are kept in an orderly and dustproof condition, while at the same time enabling the purchaser to readily see what is in the various containers without moving the containers or withdrawing the goods. The containers are arranged to be manipulated by the purchasers themselves, and any package withdrawn without calling on a clerk for assistance.

A further and important object of the invention is to arrange a signal system in connection with the containers so that when any container is emptied of its contents a signal will be given at a centralized station. This will notify the clerk or other attendant that a purchase has been made and at the same time will advise him just which container out of all those in the store has been emptied. This enables him to refill the container with the particular goods dispensed therefrom without loss of time and without necessitating a detailed inspection of all the containers to ascertain their condition.

This arrangement not only lessens the number of clerks necessary in running the store but enables a check on the purchases to be readily kept and makes it easy to keep the proper stock of goods in the containers at all times.

These objects I accomplish by means of such structure and relative arrangement of parts as will fully appear by a perusal of the following specification and claims.

In the drawings similar characters of reference indicate corresponding parts in the several views:

Fig. 1 is a fragmentary perspective elevation of a sales case, showing a plurality of

my improved containers mounted therein.

Fig. 2 is a transverse section of the case with the containers therein, in connection with a diagrammatically shown signal system.

Fig. 3 is a cross section on the line 3—3 of Fig. 2 enlarged.

Referring now more particularly to the characters of reference on the drawings, the case in which the containers are mounted includes vertical and longitudinally spaced partitions 1 open to the front, connected at their rear ends by a wall 2 and on the top by a cover 3, these parts together forming a rigid structure just as is a book-case or the like. The height of the partitions 1 is sufficient to receive a number of vertically spaced individual containers. Each container comprises a bottom plate 4 mounted for horizontal sliding movement between rollers 5 which are mounted in yokes 6 secured to adjacent faces of adjacent partitions 1.

The inner end of the plate 4 is provided with an upturned flange 7 adapted to abut against the innermost yokes 6 when the plate has been withdrawn a certain distance. A spring 8 acts to pull the plate inwardly when the flange 7 abuts against a stop-block 9 of rubber or the like fixed on the wall 2.

The outer end of the plate 4 is bent upwardly to form a finger grip or handle flange 10. Intermediate the ends of the plate 4 a rigid plate 11 projects upwardly from said plate 4, having on its lower end a horizontal and outwardly projecting flange 11^a, which is spaced from the plate 4 by an insulation pad 12 therebetween. Located between the plate 11 and the flange 10 is another vertical plate 13, secured to the plate 4 by a spring hinge 14 which acts to swing the upper end of the plate 13 inwardly. Mounted in rigid connection with the plate 13 and projecting toward the plate 11 is a horizontal plate extension 15, located a certain distance above the flange 11^a but overhanging the same. The extension 15 preferably has small side ears 16 projecting upwardly therefrom.

The container is designed to receive a standard package 17 between the plates 11 and 13, the package resting on the plate 15 between the ears and maintaining the plates 11 and 13 in spaced parallel relation. The front plate 13 is preferably provided with a glass window 18 so that the purchaser can

see the covering and name on the package without pulling out the container. When desiring to remove the package he grasps the flange 10 with one hand and slides the container outwardly, the outward movement permitted the container being sufficient to bring the inner plate 11 outwardly of the front of the casing. Holding the container out with one hand he grasps the package with the other and removes it from between the plates, either by a vertical movement or by tilting the package transversely. He then releases the container whereupon the spring 8 will at once withdraw the container into the case. As soon as the package is removed from the container, the spring hinge 14 acts to tilt the plate 13 inwardly, which causes the extension 15 to engage the flange 11^a as shown in Fig. 2.

20 This causes a signal to be given at a predetermined point such as adjacent the prescription counter or the cashier's desk by means of the following structure:

25 Mounted at such point is a channel containing a plurality of lights 19, preferably of low voltage. There is one light for each container and they are arranged in numerical sequence and order corresponding to the arrangement of the containers in the 30 various cases. One wire 20 from each light is connected to the plate 11 of the corresponding container, with sufficient slack between the wall 2 and the plate, as shown at 21, to permit of the necessary horizontal 35 movement of the container without straining the wire. The other wire 22 from said light is electrically connected to the extension 15, with a source of current such as a battery 23 interposed therein. In the present 40 instance I have shown the entire case, as well as the plates 4, 13, and 15, and the rollers 5 and hinges 14 as being of metal, so that a single wire 22 common to all the lights and containers may be connected at 45 any desired point to the case as shown.

50 It will therefore be seen that as long as any package maintains the corresponding plates 11 and 13 in their properly spaced relation, the circuit to the corresponding light will remain open and such light will not be lit. As soon as the package is removed, and the member 15 contacts with the flange 11^a the circuit is closed through the light giving the necessary signal, and such light will remain lit until the clerk refills the container with a package and separates the plates.

55 While I have shown each container as being arranged to hold only a single package, the width of the containers may be such as to hold a number of transversely spaced packages. In this case the plates 11 and 13 would be maintained in spaced parallel relation until the last package is removed. 60 Also while I have shown the plates 11 and

13 as being straight to fit against the sides of a square or rectangular package, they may of course be made curved or otherwise shaped to fit packages having different exterior contours.

70 In the event that the signal system should not be used, visual evidence of the full or empty condition of the containers will be easily noted by the inward slope of the front plate of an empty container, as shown in Fig. 1.

75 From the foregoing description it will be readily seen that I have produced such a device as substantially fulfills the objects of the invention as set forth herein.

80 While this specification sets forth in detail the present and preferred construction of the device, still in practice such deviations from such detail may be resorted to as do not form a departure from the spirit 85 of the invention, as defined by the appended claims.

85 Having thus described my invention what I claim as new and useful and desire to secure by Letters Patent is:

90 1. In a self-selling sales apparatus, a container, supporting means for a package provided with the container, said supporting means including vertical plates insulated from each other and between which the package fits, a horizontal flange at the bottom of one plate and a horizontal extension on the other plate above and overhanging the flange and means acting to tilt the plate having the extension toward the other plate 100 to cause the extension and flange to engage, and functioning only when the container is empty.

95 2. A self-selling sales apparatus including a container, said container comprising a bottom plate, a rigid vertical transverse plate projecting upwardly therefrom, another plate parallel to said rigid plate in front of the same and hinged onto the bottom plate, said plates being spaced to receive 110 a package therebetween and the bottom plate then supporting the package, and spring means acting to tilt said front plate toward the inner plate and functioning only when the package is removed.

115 3. In a self-selling sales apparatus, a case, a container for an individual package slidably mounted therein, said container including a front plate to align with the front of the case, and means provided with each container behind the front plate for causing a package supported by the container to maintain the front plate in a vertical position, and means whereby upon the removal of the package the front plate will tilt inwardly 120 whereby to present visible evidence from the front of the case as to the emptiness of the container.

125 In testimony whereof I affix my signature.
JOSEPH S. COCHRAN.
